(57) **CLAIM**

The ornamental design for a ski carry pad, as shown and described.

DESCRIPTION

FIG. 1 a perspective view of a ski carry pad,

FIG. 2 is a top view of the ski carry pad,

FIG. 3 is a side view of the ski carry pad; and,

FIG. 4 is an end view of the ski carry pad.

The broken lines illustrate environmental structure and form no part of the claimed design.
